UNITED STATES PATENT OFFICE.

JOHN J. GETGEY, OF TULSA, OKLAHOMA.

GARMENT HANGER AND PRESSER.

Application filed November 21, 1921. Serial No. 516,802.

To all whom it may concern:

Be it known that I, JOHN JACOB GETGEY, a citizen of the United States, residing at Tulsa, in the county of Tulsa and State of Oklahoma, have invented new and useful Improvements in Garment Hangers and Pressers, of which the following is a specification.

This invention relates to devices for keeping garments in shape, particularly trousers, and has for its object the provision of a novel device which constitutes a combined trousers hanger and presser, the device embodying various novel features of construction and being incidentally of such arrangement that the various parts may be disconnected and folded whereby to be disposed in a compact bundle for convenience in transportation or storage.

An important object is the provision of a device of this character which is adjustable whereby to be used efficiently for holding the shape and imparting shape to trousers of different width in the leg portions.

Another object is the provision of a device of this character in which the pressing members proper may be disconnected from the support so that the latter may be used simply as a hanger for the garment.

A further object is the provision of a device of this character which is provided with novel clamping means for holding the various elements of the device in trouser pressing position, other clamping means being provided at the joint of the pressing members for preventing them from casual displacement.

An additional object is the provision of a combined device of this character which will be simple and inexpensive in construction, easy to assemble and disassemble, simple to operate, highly efficient and positive in action, durable in service and a general improvement in the art.

With the above and other objects and advantages in view, the invention consists in the details of construction to be hereinafter more fully described and claimed, and illustrated in the accompanying drawings in which,

Figure 1 is an elevation of my device ready for use as a trouser presser.

Figure 2 is an edge view thereof.

Figure 3 is a detail sectional view on the line 3-3 of Figure 1.

Figure 4 is a detail sectional view on the line 4-4 of Figure 1.

Figure 5 is an enlarged view of one of the clamping members showing it in inoperative position.

Figure 6 is a detail view showing the means for connecting the clamping members with the hanger portion.

Figure 7 is a detail perspective view of one of the clamping members.

Figure 8 is a cross-sectional view on the line 8-8 of Figure 1.

Figure 9 is a perspective view showing the various elements of the device in folded position.

Referring more particularly to the drawings, I have shown my device as comprising a hanger member which is formed of a pair of elongated boards 10 which preferably have their confronting bases slightly recessed as indicated at 11 for the accommodation of the seams formed at the cuffs of trousers, it being of course designed that these two board members 10 be disposed at opposite sides of the trousers to be either suspended or pressed as the case may be. Secured upon the board members 10 are wire arms 12 which are of angular shape as shown and which are formed near the corners of the board with loops 13. The other end portions of the wire members 12 are arranged in a V-shape as indicated at 14 and are connected at their ends with one another and also with a suspension 15. Slidable upon the V-shaped portion 14 of the wire members is a slip-ring 16 which may be slid downwardly toward the board members 10 whereby to urge the latter into clamping engagement with the cuffs of trousers to be either pressed or supported.

The numeral 17 designates presser members in general which are suspended from the loops 13. Each presser member 17 includes two similar members each formed of upper and lower sections 18 and 19 respectively which are hingedly connected by means of strips 20 of flexible material suitably secured to the meeting ends of the sections. The upper ends of both of the sections 18 of each pair carry elongated flexible members 21 which are inserted through the loops 13 and which carry hoops 22 engageable within eyes 23 whereby the flexible members 21 may be secured in looped engagement upon the loops 13 as clearly dis-

closed in Figures 1 and 2. By this construction it will be readily apparent that the presser members 17 may be quickly and easily engaged with and disengaged from 5 the supporting member formed by the boards 10 and the wire frames carrying the same.

The sections 18 and 19 of each pair of presser members are wedge-shaped in cross-section as clearly indicated in Figure 3 and it is intended that the forward and rear edges of the trousers to be pressed be engaged between the sections of the respective presser members in a manner which will be 15 readily apparent. In order to exert clamping action between the sections, I make use of a plurality of V-shaped clamps 24 each of which is formed from a single length of resilient material and all of which are arranged upon the members 17 in straddling relation thereto. Each clamp 24 has one side formed with an elongated slot 25 through which passes a securing member 26 which is driven or otherwise secured to one 20 of the sections of the members 17 as clearly shown. It will be apparent that when the members 24 are forced upon the assembled sections constituting the members 17 that the members 17 will exert a clamping action 25 upon the edges of the garment disposed therebetween so as to provide the much desired crease in the trousers. The provision of the elongated slot 25 permits the necessary movement of the clip or clamp 24 into 30 its clamping position and also permits movement thereof into its disengaging position.

In order to adjust the positions of the pairs of members 17 so as to adapt them for use upon trousers of different widths in the 40 leg portions, I provide bars or rods 27 which are pivoted at 28 at one end and which have their other ends formed with notches 29 selectively engageable with hooks 30 carried by the other members 17. By this connection it will be seen that the members 17 may be adjusted toward or from each other by engaging the hooks 30 within the desired ones of the notches 29 and this adjustment will hold the pairs of members 17 in the 45 proper adjusted position.

As previously stated the sections 18 and 19 of each of the members 17 are hingedly connected by means of the flexible members 20 described. It is therefore essential to 55 provide some means for preventing swinging movement at this joint under ordinary conditions. In order to effect this, I make use of a plurality of V-shaped clips or clamps 31 which are permanently associated 60 with the proper sections and each of which has one leaf or arm portion formed with a longitudinal slot 32 and a cross-intersecting slot 33. These clamps or clips 31 are held in association with the sections 18 by suitable 65 fastening members 34 which may naturally

be screwed, nailed or the like, these fastening members being passed through the longitudinal slots 32 as clearly disclosed. When the fastening members 34 are in the longitudinal slots 32 and the clamping members 70 31 are pressed onto the members 17 it will be readily apparent that the members 31 will cover the hinged joints of the sections 18 and 19 so that swinging movement thereof will be prevented. Whenever it is desired to break the joint, it is merely necessary that the operator grasp the various clips or clamps 31 and pull the bight portions thereof away from the members 17 until the fastening members 34 come opposite the 80 transverse slots 33 whereupon it is merely necessary to push the clips or clamps 31 longitudinally of the members 17 to dispose the fastenings 34 in the transverse slot 33 whereupon the clamping members 31 will not be disposed over the hinged joints and then the sections 18 and 19 may be folded one upon the other.

In the use of the device when it is desired to press a pair of trousers, it is first necessary to slide the ring 16 upwardly so that the board members 10 will be separated. At the same time the clamps 24 and 31 must be moved laterally with respect to the elements 17 so that the sections 18 and 19 of the respective members 17 may be separated. The cuff portions of the trousers are then engaged between the boards 10 after which the clip ring 16 is forced downwardly to cause the board members 10 to exert a 90 clamping action upon the trousers cuff. The forward and rear edges of the trousers, that is the portions where it is desired to produce a crease, are engaged between the members 17, after which the clamps 24 and 31 are 95 pressed transversely of the members 17 to force the latter together and this will of course exert a clamping action upon the forward and rear edges of the trousers which will produce the much desired crease 100 105 110 115 therein. As will be noted from the drawings, the distance between the members 17 at the front and rear of the trousers may be regulated by means of the pivoted bars 27 which are provided with the notches 29 engageable upon the hooks 30 so that the device is equally well adapted for use in working upon trousers which are narrow or wide through the legs as the case may be.

When the use of the device is not desired, 120 it is readily apparent that the rods 27 may be disengaged from the hooks 30 and swung upon their pivots 28 whereby to lie within recesses 35 formed in the edges of one set of the members 17 and that the clips or clamps 125 24 may be slid laterally with respect to the associated elements 17 so that the clamping action will be no longer exerted.

It is of course necessary that the clamping members 31 be likewise slid laterally 130

and then be moved longitudinally of the members 17 so as to bring the securing members 34 within the transverse slots 33, whereupon the respective members 18 and 19 may be swung one upon the other. The hooks 22 are of course disengaged from the eyes 23 so that the members 17 formed of the sections 18 and 19 may be entirely disengaged from the clamping and supporting portion of the device. When the parts are thus removed and folded it is apparent that they may be bundled into compact form as illustrated in Figure 9 and be secured by means of an elastic band, a piece of string or the like so that a compact bundle will be formed which will be convenient in transportation and storage.

From the foregoing description and a study of the drawings it will be apparent that I have thus provided a simply constructed and consequently very inexpensive device which is equally well adapted for use in merely supporting or suspending trousers or in pressing the same so as to restore them to their proper shape and to provide the much desired creases thereof. Owing to the simplicity of the construction it is apparently seen that there is practically nothing to get out of order and the device will consequently have a long life and satisfactorily perform all the functions for which it is intended.

While I have shown and described the preferred embodiment of the invention, it is of course to be understood that I reserve the right to make such changes in the form, construction and arrangement of parts as will not depart from the spirit of the invention or the scope of the subjoined claims.

Having thus described my invention I claim;

1. A device of the character described comprising a clamping member adapted to be clampingly engaged upon the cuff ends of trousers, said clamping member including supporting loops, a pair of presser members detachably and pivotally connected with each of said loops, each of said presser members being wedge shaped in cross-section and being formed of jointed sections, means for holding said presser members in spaced relation, clamping means holding the asso-

ciated sections of the presser members in clamping engagement with trousers at the forward and rear edges of the latter, and means embracingly engaged upon the members at the joints for preventing swinging movement at said joints.

2. A device of the character described comprising a clamping member adapted to clampingly engage upon the cuff ends of trousers, said clamping members including supporting loops, a pair of presser members detachably and pivotally connected with each of said loops, each of said presser members being wedge shaped in cross-section and being formed of hingedly connected sections, means for holding said presser members in spaced relation, clamping means holding the associated sections of the presser members in clamping engagement with trousers and the forward and rear edges of the latter, and means slidably engaged upon the members at said joint for preventing swinging movement at said points, said means comprising V-shaped clamps laterally longitudinally adjustably mounted upon the presser members and formed with longitudinal slots intersected by transverse slots, and securing members passing through said longitudinal slots into the associated presser members.

3. A device of the character described comprising a clamping member adapted to be engaged upon the cuffs of trousers and including hanger elements, a pair of presser bars suspended from said hanger elements and adapted to be engaged upon the edges of trousers, each of said presser members being formed of two bars formed in sections connected by flexible elements, and means engaged upon the presser members at said joints for holding the sections in extended rigid relation and in clamping engagement, said means consisting of metallic elements mounted for sliding movement transversely of the presser members for effecting compression thereof, said metallic elements being slidable longitudinally of the presser members out of obstructing relation to said joints.

In testimony whereof I affix my signature.

JOHN J. GETGEY.
